COLLAPSIBLE AND CONVERTIBLE
ENCLOSURE FOR INFANTS

Frederick M. Bishoff, Arlington, Va.

Application August 23, 1950, Serial No. 180,995

12 Claims. (Cl. 5—99)

1

This invention relates to a foldable inclosure for infants and more particularly to an improved inclosure which is easily collapsible for storage purposes and capable of conversion from an inclosure to a child's table or desk.

The infants' inclosures commercially available and commonly termed "play pens" are normally provided with a split floor which folds upwardly and two split side panels which fold inwardly to collapse the play pen for storage. Play pens of this type are difficult to collapse since the floor segments must be held in their upwardly folded positions while the side panels are being inwardly folded. The use of a split floor is also disadvantageous in that there is a tendency for one section to sag below the other with consequent danger of trapping and clamping the infant's feet in the split between the two segments.

It is a general objective of this invention to overcome the disadvantages outlined above and to provide a play pen or similar inclosure which is not only more readily collapsed but also suitable for conversion to other types of children's furniture.

A more particular object of the invention lies in the provision of a play pen having an unsplit rigid floor and unsplit rigid side panels which are pivotally turnable from their vertical inclosure defining positions to horizontal folded positions overlying the floor.

A further object of the invention lies in the provision of an inclosure whose side panels are slidably and pivotally secured to corner posts upstanding from a base member so as to permit folding of the walls in any sequence to overlie the base member.

Still another object of the invention lies in the provision of an inclosure having a base member, side panels and panel supports, the panels and panel supports being both readily attachable to each other and to the base member as well as readily detachable from each other and from the base member.

A further object of the invention lies in the provision of an inclosure for infants having a hollow base member, readily attachable and detachable panel supports and panels which, when detached, are receivable in the hollow base for storage or transporting purposes.

A still further object of the invention lies in the provision of an inclosure for infants having a solid, rigid floor, upstanding panel supports, and separable inclosure panels which, when detached from the panel supports, permits of the

2

inversion of the floor and panel supports to form a child's play table.

Still another object of the invention lies in the provision of an inclosure for infants having a hollow base member, upstanding panel supports and separable inclosure defining panels which, when detached from the supports, permits the base member to be inverted to form a desk-like structure supported on the panel supports, 10 the hollow interior of the base member forming a drawer-like compartment.

A still further object of the invention lies in the provision of a foldable play pen having readily separable panels and panel supports, and convertible from an inclosure to a table or desk-like article for infants' play, and which is of simple construction, capable of economic fabrication.

I achieve these objects and such other objects, 20 advantages and features as may hereinafter appear or be pointed out in the manner shown by the several embodiments illustrated in the appended drawings, wherein:

Figure 1 is a perspective view of an inclosure set up for use as a child's play pen.

Figure 2 is a perspective view showing certain of the side panels folded into their storage positions.

Figure 3 is an enlarged section taken along line 3—3 of Figure 1.

Figure 4 is an enlarged perspective view of one of the corner posts.

Figure 5 is an enlarged section taken along line 5—5 of Figure 1.

Figure 6 is a perspective view showing a different embodiment of the corner post together with means for slidably and pivotally securing a side panel thereto.

Figure 7 is a perspective view of the fastener utilized to secure the upper ends of the side panels together in their inclosure defining positions.

Figure 8 is a plan view of the fastener in use at one corner of the inclosure.

Figure 9 is a side elevation of the fastener taken along line 9—9 of Figure 8.

Figure 10 is an elevational view of the play pen in its folded condition and turned upon its side for storage carrying purposes.

Figure 11 is a perspective view of a modified inclosure shown partially disassembled.

Figure 12 is an enlarged section taken on line 12—12 of Figure 11.

Figure 13 is a section taken on line 13—13 of Figure 12.

3

Figure 14 is a reduced perspective view of the inclosure shown in Figure 11 with the side panels removed and the base member inverted to form a table or desk-like article.

While the invention is described and illustrated herein with a particular reference to an infant's inclosure of the type known as a "play pen," it will be understood that it is broadly applicable to inclosures of other types such as strollers and cribs and is not necessarily limited to a play pen.

Referring to the drawings, and more particularly to Figures 1 through 5 and 8 through 10, the play pen is shown as comprising a generally rectangular inclosure 10 formed of wood or similar suitable material. An unsplit floor or base member 11 is provided upon which may be separately supported a floor mat 12 of suitable soft material. The base member is preferably square as shown although certain of the objectives may be obtained by forming the base member as an open rectangular framework, as for example, for use as a child's stroller. A panel support or corner post 20, best shown in Figure 4 extends upwardly from each corner of the base member. The corner post is preferably square or rectangular in cross section, although it may be of other shape, and is provided with a square slot 21 which receives the corner of the base member and in which the base member may be permanently secured as by cement or glue or temporarily secured as by dowels or screws. The two sides of the corner post which face other corner posts in the assembled pen, are longitudinally grooved at 22, and from the upper ends of these grooves are extended lateral or horizontally positioned grooves 23 which open into the aforementioned sides of the corner posts. The lower ends of the corner posts are provided with openings, not shown, which removably receive the spindles of conventional caster assemblies as indicated at 25 in Figure 1.

The inclosure is defined by a plurality of side panels 30 which are preferably of equal size. The side panels are formed as an open framework having upper and lower rails 31 and 32 respectively and side frame members 33 and 34. The opening within the frame members is traversed by spaced rods 35 which are preferably horizontal rather than vertical to better enable the infant to lift himself and to exercise therefrom. Each panel is provided close to its lower edge with a pair of sidewardly extending trunnions or pivot pins 36 which are fixedly secured to the panel frame members 33 and 34 in any desired manner as by force fit insertion into sockets therein.

The adjacent panels 30 are held together in inclosure defining vertical positions at their upper edges by means of a fastener element 40, best shown in Figures 7, 8 and 9. The fastener is preferably formed of metal or similar material and provided with two sides 41 at right angles to each other and meeting to form a corner edge 42. At the upper end of the fastener an integral web 43 connects the side walls 41 to rigidify the fastener and also provide for finger grasping. Each side wall 41 is slotted as indicated at 44 with the slots opening into the lower edges of the fastener. The frame members 33 and 34 of the side panels 30 are provided at their upper edges with headed members such as rivets or screws shown in Figures 8 and 9 at 38. To fasten the side panels in their inclosure defining positions it is only necessary to slide the

4

fastener 40 downwardly engaging the slots 44 under the heads of the elements 38. When it is desired to collapse or fold the play pen, the fasteners are removed by inserting a finger under web 43 and lifting the fastener out of engagement with the headed members 38.

To assemble the inclosure for play pen use, each side panel 30 is secured to a pair of corner posts 20 by inserting the trunnions 36 in the lateral grooves 23 and moving the trunnions until they register with the vertical slots 22. When a pair of panels have been thus inserted and then lowered to the bottoms of slots 22 a fastener 40 is applied to the headed elements 38 in the manner previously described and serves to hold the panels in their vertical positions. The remaining panels may be individually applied and fastened to each other in a similar manner. Space 37, between the panels and the corner posts is preferably made large enough to receive the pins 36 and thus readily permit attachment or detachment of the panels.

When it is desired to collapse the play pen inclosure for removal to another site, or for storage, any two of the fastener elements 40 may be first removed and the panel intermediate them allowed to turn into a horizontal position about its trunnions riding in grooves 22. Another fastener may then be removed and a second panel 30 turned down into a horizontal position overlying the first panel and the base member as shown in Figure 2. Ordinarily in turning about its trunnions the second panel will be raised by contact with a portion of the first panel and the trunnions of the second panel will be elevated thereby in grooves 22 of the corner posts. However, if desired, the second panel may be slightly lifted before it is turned into its horizontal position to clear the already folded panel. The remaining two panels may be individually turned, or lifted and turned, into their horizontal positions overlying the first two panels upon removal of the remaining fastening elements 40. The panels may be folded of course in any desired sequence. When thus collapsed the play pen is flat and occupies only that space defined by the area of the base member and the height of the corner posts, the side panels being in engaging, overlying relation and spaced from the base member by the floor pad 12, if the latter is left in place while the pen is folded. The folded pen may be rolled in its horizontal position, or turned on one side and carried, or otherwise transported, to a suitable storage area. When turned in the manner shown in Fig. 10, it will be noted that the last folded side panel hangs downwardly and retains the other panels in their folded positions.

If desired, the side panels instead of folding may be readily detached from the corner posts, after the fasteners have been removed, by lifting each panel to the upper ends of grooves 22, so that pins 36 align with lateral grooves 23, and then moving the panel horizontally with its pins riding in grooves 23 until separation is accomplished. When this is done, and upon removal of the castors, the base 11 may be inverted to form a table-like surface, for child's play, supported on posts 20 acting as table legs.

In Figure 6 there is shown a modified version of the panel supporting corner posts along with modified slidable panel pivot means. In this embodiment the corner posts 20' may be made cylindrical or rectangular. The trunnion pin retaining slots 22 are omitted. Over the corner

post 20' is slidably received a loop member 70 shaped to conform with the cross section of the corner post and vertically slidable thereon. Extending from one portion of the loop 70 is an integral pivot pin 71 which is pivotally received in a socket opening 72 formed in the ends of the lower panel frame members 32. The pin fit may be a loose one, or if desired, suitable ring-like and resilient detent means not shown may be provided in the socket 72 to conveniently grasp a grooved end of the pivot pin 71 and prevent separation from the panel until sufficient force is exerted to overcome the detent means. It will be apparent that a panel thus pivotally attached to post 20' is capable of turning about 15 the pin 72 as an axis and at the same time moving rectilinearly with respect to the post by means of the sliding engagement of loop 70 thereon.

The modified play pen shown in Figures 11 through 14 is similar in construction to that previously described but differs in several important respects. The base member instead of being a flat planar member is increased in height and made hollow. As will be noted from Figure 11, the modified base member 50 is formed of upper and lower walls 51 and 52 and side walls 53, 54 and 55. These walls provide a hollow interior forming a compartment 56 open to one side of the base for a purpose to be hereinafter described.

The corner posts 60 in the modified play pen are similar to corner posts 20 except that the castors of the lower ends are omitted and in place thereof the posts are made readily separable and attachable. One way of providing this feature is by forming each post 60 with rabbets 61 on two opposed side faces. At each corner of the upper wall 51 of the base there is affixed a post securing bracket 62 by any desired means such as screws or the like, not shown. Each bracket has a pair of upstanding parallel side walls 63 each of which is flanged inwardly toward the other as at 64. An upstanding flange 65 closes one end of the bracket while the other end is open to permit ingress and egress of the corner post 60. The corner post is readily attached to the base member by inserting the corner post in the open end 66 of the bracket and sliding the post to an abutting relationship with the closed end or flange 65. During this movement the rabbets 61 slidably receive the inturned flanges 64 which are preferably so formed as to provide resilient, frictional resistance to ingress movement of the corner post. Detachment of the corner post is of course readily accomplished by movement of the post in the opposite direction against the friction of flanges 64.

Four corner posts 60 may be readily attached to the base 50 in the manner described above. After such attachment the side panels 30 may be assembled and fastened in inclosure defining positions in the same manner as previously described for the embodiment shown in Figure 1. After use as a play pen, the panels may be turned into horizontal positions overlying the base in the same manner as described for the embodiment of Fig. 1 or each panel may be detached from the corner posts, as previously described, and laid in the compartment 56, several side panels being shown stored in this manner in Figure 11. The compartment is preferably of such size as to be capable of receiving for storage, all four panels, one above the other, and a floor mat, and still leave space, as indicated at A in Figure 11, for

receiving the four corner posts 60 and the fastener elements 40, upon their detachment.

If it is desired to utilize the play pen shown in Figure 11 as a table or desk it is only necessary to detach the four side panels 30 and invert the base member 50 so that it will be supported upon the corner posts 60 as shown in Figure 14. When turned into this position the lower surface 52 forms a table or desk top and the upper surface 51 together with the walls 53, 54 and 55 form a drawer-like compartment in the desk suitable for holding the play toys of the child.

It will be observed from the description above that my improved play pen may be readily assembled or disassembled without the need for tools or other special equipment by merely interengaging the separate component parts. All of the parts are of relatively simple construction and many are duplicates in size and shape so that the pen may be practically constructed at low cost. When assembled the inclosure may be readily collapsed by simple lifting and turning movements without requiring a set sequence of operations, and when thus folded or collapsed occupies a minimum of space. The play pen of Fig. 1, upon removal of its side panels, may be readily inverted and converted into a table while the play pen of Fig. 11 may be easily converted in a similar manner to a desk for utilization by an infant in his play. In the modification shown in Figure 11 of the parts may be readily disassembled and placed in the base member which provides a convenient packing or storage container.

It will be apparent that modifications may be made in the illustrated embodiments by those skilled in the art without necessarily departing from the spirit and scope of the appended claims.

Having thus described and illustrated my invention, what I desire to secure by grant of Letters Patent is:

1. A foldable inclosure for infants comprising a rectangular floor having upstanding corner posts, a plurality of side panels, releasable means for fastening the panels together in substantially vertical inclosure defining positions, each of said corner posts being provided with a pair of vertically extending grooves facing toward adjacent corner posts and trunnions on each of said panels slidably fitting into said corner post grooves, whereby the panels may be folded to overlie said floor by successively turning the panels about their sliding trunnions.

2. A collapsible and convertible infants' inclosure comprising, a rectangular floor, corner posts extending upwardly from said floor, and readily attachable and separable inclosure side panels slidably pivoted to said corner posts, said panels when attached and turned to upright positions forming an infants inclosure, said panels being foldable to collapsed condition of the inclosure by successively lifting and turning each panel to overlie said floor, the detachment and separation of said panels permitting inversion of said floor to form a table surface supported on said corner posts.

3. An inclosure for infants comprising, a base member having a hollow interior forming a compartment, spaced posts extending upwardly from the upper surface of the base member, means for readily attaching and detaching said posts, inclosure forming side panels upstanding from the upper surface of said base member secured to said posts, and means for readily attaching and detaching the side panels, said side panels and

posts when detached being receivable in said compartment for storage.

4. An inclosure for infants as set forth in claim 3 wherein, said base member compartment is open to one side of the base and upon detachment of the side panels the base member may be inverted and supported on said posts to form a desk-like body having a drawer-like compartment.

5. An inclosure for infants as set forth in claim 3 wherein, said panels are provided with means for slidably moving along said posts including means for turning the panels from their upstanding inclosure defining positions to positions overlying said base member.

6. A foldable inclosure for infants comprising, a base member, a plurality of side panels, releasable means for fastening the upper ends of adjacent panels together in substantially vertical, inclosure defining positions, upstanding posts carried by said base member and means on each of said posts for slideably and pivotally supporting the adjacent lower ends of a pair of panels, whereby all of said panels, upon release of said fastening means, may be folded into substantially horizontal, overlying and juxtaposed positions by lifting each panel successively to clear previously folded panels and turning each panel about said slideable pivot means.

7. A foldable inclosure as set forth in claim 6 wherein, said means for slideably and pivotally supporting the panels to the posts comprises pivot pins extending from the lower ends of each panel and a pair of sockets in each of the posts receiving said pivot pins from adjacent paired panels for rectilinear and turning movements.

8. A foldable inclosure as set forth in claim 6 wherein, said means for slideably and pivotally supporting the panels to the posts comprises loop members slideably receiving the posts and having extension pins pivotally received in sockets in said panels.

9. An inclosure for infants comprising, a base member, a plurality of upstanding posts carried by said base member, and vertical, inclosure defining side panels provided with trunnions extending from their ends, each of said posts having a pair of longitudinally extending grooves each of which is provided with a laterally extending groove communicating therewith and with an exterior surface of said post, said lateral grooves slideably receiving said side panel trunnions for assembly of the side panels to the posts and for separation therefrom, and said longitudinal grooves slideably and pivotally receiving said trunnions for successively lifting and turning all of the panels to folded, overlying and

juxtaposed positions covering said base member.

10. An inclosure for infants comprising, a base member carrying a plurality of upstanding posts and inclosure defining side panels provided with trunnions extending from their ends, each of said posts having a plurality of exterior faces, a longitudinally extending groove in each of two faces on each post, each groove communicating with a laterally extending groove opening into a different post face, said lateral grooves slideably receiving said side panel trunnions for assembly of the panels to the posts and for separation therefrom, and said longitudinal grooves slideably and pivotally receiving said trunnions for successively lifting and turning all of the panels to folded, overlying and juxtaposed positions covering said base member.

11. A collapsible and convertible infants' inclosure comprising, a floor having spaced upstanding posts, means for readily attaching and detaching said posts to the upper surface of said floor, inclosure forming side panels upstanding from said floor and slideably pivoted to said posts and means for readily attaching and detaching said panels whereby, said inclosure may be collapsed by successively lifting and turning said panels on their slideable pivots to overlie the floor, or said inclosure may be converted to form a table by detachment of said panels and the floor inverted for support on said posts, and said inclosure may be completely disassembled by separation of said posts and said panels from each other and from said floor.

12. An infants' inclosure as set forth in claim 11 wherein, said means for readily attaching and detaching the posts comprise brackets secured to the floor each having a pair of upstanding parallel sides with flanges inturned toward each other and said posts are provided with rabbets for slideably receiving said inturned flanges.
